UNITED STATES PATENT OFFICE.

GEORGE C. EGGERS, OF BOVILL, IDAHO.

RULING FOUNTAIN-PEN.

1,149,348.

Specification of Letters Patent. Patented Aug. 10, 1915.

Application filed March 2, 1914. Serial No. 821,949.

To all whom it may concern:

Be it known that I, GEORGE C. EGGERS, a citizen of the United States, residing at Bovill, in the county of Latah and State 5 of Idaho, have invented new and useful Improvements in Ruling Fountain-Pens, of which the following is a specification.

This invention relates to improvements in ruling fountain pens.

10 It is one of the objects of this invention to provide a pen of this character with pen blades and a feeder which are mounted in the handle by yielding means in such a manner that said means will function to support 15 both the pen blades and the feeder in position, with respect to the handle.

A further object is to provide a novel construction whereby said means will not only 20 function to support said pen blades and feeder, but also, to close the handle against leakage of ink therefrom.

25 Further objects and novel features of the invention will be more fully described in the accompanying drawing, and will be more particularly pointed out in and by the appended claims.

In the drawing, Figure 1 is a view in elevation of my improved ruling pen with the cap omitted. Fig. 2 is a sectional view, 30 partly in elevation, on line 2-2 of Fig. 1. Fig. 3 is a view similar to Fig. 2, taken on line 3-3 of Fig. 2. Fig. 4 is a sectional view of the feeder, taken on line 4-4 of Fig. 3. Fig. 5, is a sectional view on line 35 5-5 of Fig. 3.

Like characters of reference designate similar parts throughout the different figures of the drawing.

As illustrated, 1 designates a hollow tubular barrel or handle having one end open and adapted to receive the fluid, which is to be used in the pen. A cap 2 is provided to protect the pen blades and fit over the handle 1, as indicated in Fig. 2.

40 I provide opposing ruling pen blades 3, which are bowed, as indicated at 4, to provide the necessary resiliency for maintaining the terminal ends 5 in close contact with each other. The terminal ends 5 are in the 45 form of flat blade-like portions, which are provided with longitudinally disposed slits 6 extending inwardly from said ends where-through the ruling fluid passes to the ruling ends. The blades 3 converge from the bowed portions 4 to the pen or blade ends 5, and said blades converge, as indicated at

7 from the bowed portions 4, rearwardly. At the terminal of such latter convergence, the pen blades extend outwardly, as at 8, and the same are provided with extensions 60 9, which closely fit against the interior of the barrel or handle 1.

My improved feeder comprises an elongated solid strip 10, which is preferably oval in cross section and which I have shown provided with exteriorly and longitudinally disposed recesses 11, which form feeding ducts. The feeder 10 is disposed between the pen blades and extends approximately to the terminal ends thereof or as nearly to the 70 terminal ends as is possible in order to permit said ends to be disposed in engagement with each other. As illustrated more particularly in Fig. 3, the end of the feeder terminates near the bases of the slits 6 and contacts with the pen blades.

In order to mount the feeder between the pen blades, I provide means in the form of a packing disk 12, which is of yielding material and which is held in place between 80 the extensions 9, the portions 8 forming abutments for the packing means 12. The packing means is suitably apertured for projection therethrough of the feeder 10, so that the latter will be mounted in the packing 85 12 and will be held against displacement from a true axial position by engagement with the converging terminal ends of the blades, it being my purpose to mount the feeder at two longitudinally spaced points. 90 I preferably provide packing 12 which is sufficiently soft to snugly embrace the feeder 10, but which is not sufficiently yielding to project into and fill the ducts 11 and thereby interfere with proper feed of the fluid. 95 The feeder 10 projects inwardly past the packing 12 so as to always be in effective fluid receiving proximity with the contents of the handle 1.

It will be seen from the foregoing that 100 the packing 12 constitutes a feed passage closure for the open end of the handle inasmuch as it functions to close the open end of the handle except for feed passage of the fluid in the feed ducts.

105 By reason of the fact that ducts 11 are provided on opposite sides of the feeder 10, it will be seen that the pen will be operative irrespective of the pen blade which happens to be lowermost when the pen is positioned 110 for use.

I have found in practice that the feed pro-

vided by my invention is so efficient that when the pen blades initially engage the paper a full broad line, equal to the width of the pen blades will result from initial 5 contact of the blades throughout the length of the line drawn. Furthermore, by locating the slits nearer the margins of the pen blades than to the center thereof, I find that the line drawn is never ragged on the edges 10 but is continuous and unbroken throughout its width.

While I have herein shown and described one specific form of my invention, I do not wish to be limited thereto except for such 15 limitations as the claims may import.

I claim:—

1. In a fountain ruling pen, a hollow handle 20 for the fluid, a pen blade structure mounted in the handle and having bowed flat pen blades converging to dispose their terminal ends in abutting relation, a feeder extending from the interior of the handle toward and between and in contact with the blade terminals and provided with exteriorly and longitudinally disposed ducts 25 delivering to said blade terminals, and means for supporting the pen blade structure and the feeder in said handle, substantially as described.

Copies of this patent may be obtained for five cents each, by addressing the "Commissioner of Patents, Washington, D. C."

2. In a fountain ruling pen, a hollow handle 30 for the fluid, opposed pen blades projecting from the handle and having extensions closely fitting the interior of the handle, a feeder extending from the interior of the handle outwardly between said pen 35 blades, and a packing of yielding material interposed between said extensions and embracing the feeder to support the latter and said blades in position, substantially as described.

3. In a fountain ruling pen, a hollow handle 40 for the fluid, independent pen blades projecting from the handle and having extensions projecting into the interior of the handle, a feeder, and handle stopper means 45 of yielding material disposed inside of said handle and engaging the latter and said blades and feeder to hold said blades and feeder in position and close the handle, substantially as described.

In testimony that I claim the foregoing as my own, I hereby affix my signature in the presence of two subscribing witnesses.

GEORGE C. EGGER.
